TELEPHONE DIALING INSTRUMENT

Ronald Binks, Chambersburg, Pa., assignor to Global Systems Design Corporation, Chambersburg, Pa.

Filed Aug. 17, 1972, Ser. No. 281,400

Term of patent 14 years

Int. Cl. D14—03

U.S. Cl. D26—14 A

FIG. 1

FIG. 2

FIG. 4

FIG. 3

FIG. 5

FIG. 6

FIG. 1 is a perspective view of a telephone dialing instrument showing my new design;

FIG. 2 is a top plan view of the telephone dialing instrument;

FIG. 3 is a front elevational view of the telephone dialing instrument;

FIG. 4 is a side elevational view of the telephone dialing instrument showing one side thereof;

FIG. 5 is a side elevational view of the telephone dialing instrument showing the other side thereof; and

FIG. 6 is a rear elevational view of the telephone dialing instrument.

I claim:

The ornamental design for a telephone dialing instrument, substantially as shown and described.
